UNITED STATES PATENT OFFICE

2,640,362

ROTARY RECIPROCATING PUMP DRIVE

Eugene D. Taylor, Kenosha, Wis.

Application January 17, 1950, Serial No. 138,960

2 Claims. (Cl. 74—22)

1

This invention appertains to a pump construction for use in the processing of food and is particularly designed for use in the dairy industry, in processing milk and other dairy products.

The primary object of the instant invention is to reduce the number of parts that come in contact with the food product being processed, so as to decrease the possibility of bacterial damage thereto.

Another important object of this invention is to enable the pump to be easily assembled and disassembled, so that the parts may be easily removed for cleaning, whereby better sanitation is achieved.

Another important object of this invention is to provide a rotary reciprocating pump, especially designed for use in processing foods.

A meritorious feature of this invention resides in the provision of a piston, which is reciprocated to perform a pumping function, and which is rotated on both strokes thereof, so as to function as a valve for controlling the inlet port and outlet port.

These and ancillary objects and additional structural features of merit are attained by this invention, the preferred embodiment of which is set forth in the following description and illustrated in the accompanying drawings, wherein:

Figure 1 is a longitudinal vertical sectional view through the pump housing and housing for the actuating means therefor, the pump housing being detachably secured to the housing for the actuating means;

Figure 2 is a transverse sectional view taken on line 2—2 of Figure 1;

Figure 3 is a transverse sectional view taken on line 3—3 of Figure 1, and,

Figure 4 is a view in perspective of the piston.

In the accompanying drawings, the piston type valveless pump 10, constructed in accordance with the principles of this invention, includes a housing 12 for the operating means 14 for the pump. The operating means includes a drive shaft 16 which is rotatably journaled in the lower end of the housing, the shaft having its inner end journaled in a bearing socket 18, which is formed laterally on the front wall 20 of the housing. The shaft extends through an opening 22 in the rear wall 24 of the housing and is mounted in suitable bearings.

A drive gear 26 is fixed on the shaft, the gear 26 being disposed in meshing engagement with a gear 28 slidably mounted on a driven shaft 30, disposed parallel to the drive shaft 16. The shaft 30 is rotatably mounted at one end in a bearing

32 extending laterally from the rear wall 24 of the housing. The shaft 30 extends through a bearing 34 in the front wall 20 of the housing and projects outwardly beyond the front wall.

5 A ring 36 is disposed concentrically on the shaft and abuts against the front wall 20 of the housing, the ring being formed on its face with a projecting annular flange 38 to receive a compressible sealing ring 40. A sectional casing 42 is detachably mounted on the front wall 20 of the housing and the front wall is formed at its upper and lower ends with lateral flanges 44 and 46 which are transversely bored and threaded from their front faces as at 48. The inner portion of 10 the projecting flange 50 from the front wall is recessed at its inner circumference to form an annular shoulder 52, which seats the closed end 54 of the circular casing. A detachable front wall 56 is provided for the casing 42 and the inner part thereof is formed with a seat 58 to abut against the edges of the side walls and form a tight joint. The wall 56 is formed with enlarged transversely apertured portions 59 through which tie bolts 60 pass, the tie bolts being threadingly 15 engaged in the bores 48 in the flanges 44 and 46 of the housing.

20 The shaft 30 is formed at its rear portion with a longitudinal slot 62, the gear 28 having a key 64 slidably disposed in the slot, so that the shaft may slide longitudinally through the front wall of the housing and at the same time be rotated by the shaft 16 and intermeshing gears 26 and 28.

25 Means is provided for reciprocating the shaft 30 and is responsive to the rotation of the shaft 16. The means is mounted on the shaft 16 and includes a cam 64 which is concentrically disposed on the shaft 16, the cam being adapted to rotate in a channel or cam track 66 in a U-shaped member 68. The web portion of the U-shaped member 68 is keyed by a pin 70 to web portions of an upstanding U-shaped member 72, the member 72 embracing the lower portion of a bearing assembly 74 and having the terminals of its upstanding ends formed with transverse openings 76 within which pins 78 are mounted, the pins 78 30 extending laterally from the outer race 80 of the bearing assembly. The inner race 82 of the bearing assembly is keyed by a transverse key 84 to the shaft 30. Thus, as the cam 64 rotates in the cam track 66, the member 68 is oscillated and the movement of the member 68 is transmitted to the U-shaped member 2 and thus to the shaft 30.

35 A piston 86 is detachably mounted on the outer end 88 of the shaft 30, the end 88 being reduced 45 axially and the shaft being formed with a rec-

tangular shoulder 90 adapted to fit in a rectangular counterbore 92 in one face of the piston.

The piston 86 includes a block 94, having opposing curved sides 96 and opposing flat sides 98. The block is formed with the counterbore 92 in one end thereof, the opposing ends being flat, and a passage 100 extends axially through the block.

Semi-circular extensions 102 and 104 extend in opposite directions from the opposing edges of the sides 98, the outer or unattached edges of the extensions being slidably disposed and in sliding contact with the inner surface of the circular walls of the casing 42. The shaft 30 terminates in an externally threaded end 106, with a nut 108 being threaded thereon to lock the piston against the shoulder 90.

The casing 42 is formed at its opposing side with an inlet 110 and an outlet 112, the inlet and outlet being longitudinally spaced and transversely opposed, so that the extensions 102 and 104 on the block 86 are alternately in closing engagement of the inlet and outlet.

It is to be especially noted that the pump casing is easily and readily attached to the housing and can be quickly removed, with the pump consisting of only one part, namely, the piston, so that it may be easily removed from the shaft and quickly and completely cleaned and sterilized.

Having described the invention, what is claimed as new is:

1. A rotary reciprocating pump comprising a housing, a drive shaft rotatably journaled in said housing, a driven shaft for the pump piston journaled in said housing and in offset parallel relation to said drive shaft, gear means actuated by the drive shaft for rotating the driven shaft in response to rotation of said drive shaft, and means interconnecting said drive and driven shafts for effecting reciprocation of said driven shaft in response to rotation of said drive shaft, said last named means including a cam disk secured to said drive shaft for rotation therewith, said cam disk lying in a plane forming an acute angle with the axis of said drive shaft, a yoke member engaged on a peripheral portion of said disk for pivoting movement in response to rotation of said disk, said yoke member having its upper end pivotally and rotatably connected to said driven

5 shaft whereby rotation of said drive shaft effects pivoting movement of said yoke member and whereby said driven shaft can be reciprocated at the same time said gear means effects rotation of said driven shaft.

2. A rotary reciprocating pump comprising a housing, a drive shaft rotatably journaled in said housing, a driven shaft for the pump piston journaled in said housing and in offset parallel relation to said drive shaft, gear means actuated by the drive shaft for rotating the driven shaft in response to rotation of said drive shaft, and means interconnecting said drive and driven shafts for effecting reciprocation of said driven shaft in response to rotation of said drive shaft, said last named means including a cam disk secured to said drive shaft for rotation therewith, said cam disk lying in a plane forming an acute angle with the axis of said drive shaft, a yoke member engaged on a peripheral portion of said disk for pivoting movement in response to rotation of said disk, said yoke member having its upper end pivotally and rotatably connected to said driven shaft whereby rotation of said drive shaft effects pivoting movement of said yoke member and whereby said driven shaft can be reciprocated at the same time said gear means effects rotation of said driven shaft, said last named means including a cam disk secured to said drive shaft for rotation therewith, said cam disk lying in a plane forming an acute angle with the axis of said drive shaft, a yoke member engaged on a peripheral portion of said disk for pivoting movement in response to rotation of said disk, said yoke member having its upper end pivotally and rotatably connected to said driven shaft whereby rotation of said drive shaft effects pivoting movement of said yoke member and whereby said driven shaft can be reciprocated at the same time said gear means effects rotation of said driven shaft, said yoke member including a pair of U-shaped elements disposed in back to back relation, a pin interconnecting said elements, one of said U-shaped elements rotatably receiving said peripheral portion of said cam disk, a bearing on said driven shaft, said other U-shaped element pivotally and removably connected to said bearing.

EUGENE D. TAYLOR.
